his Attorney.

UNITED STATES PATENT OFFICE.

BENNO B. LEUSTIG, OF CLEVELAND, OHIO.

TRAFFIC-SIGNAL FOR MOTOR-VEHICLES.

1,323,295.

Specification of Letters Patent.

Patented Dec. 2, 1919.

Application filed June 7, 1919. Serial No. 302,454.

To all whom it may concern:

Be it known that I, BENNO B. LEUSTIG, a citizen of the United States, residing at Cleveland, in the county of Cuyahoga and 5 State of Ohio, have invented a new and useful Traffic-Signal for Motor-Vehicles, of which the following is a specification.

This invention relates to improvements in traffic signals for motor-vehicles, and pertains more especially to a traffic signal comprising a tail-light, a semaphore-arm, a plate bearing the word "Stop," and a plate bearing the license number.

One object of this invention is to produce 15 a reliable and efficient traffic signal of the character indicated which is equally serviceable at night and in the daytime for indicating the direction the vehicle is about to take in turning corners or rounding curves and 20 for indicating that the vehicle is about to stop preparatory to arresting the movement of the vehicle.

Another object is to have the hereinbefore mentioned semaphore-arm illuminated at 25 night in any one of the three indicative positions into which said arm may be actuated from its downwardly pointing and normal position.

Another object is to have the hereinbefore 30 mentioned plates, supported from a bracket provided with the pivotal member from which the semaphore-arm, an actuating member for said arm and the tail-light are supported.

35 Another object is to facilitate the assemblage of the component parts of my improved device and to render said device simple, strong and durable in construction.

With these objects in view, and to attain 40 any other object hereinafter appearing, this invention consists in certain features of construction, and combinations and relative arrangements of parts, hereinafter described in this specification, pointed out in the 45 claims and illustrated in the accompanying drawings.

In said drawings, Figure 1 is a central vertical longitudinal section of apparatus embodying my invention. Fig. 2 is a vertical section taken along the line 2—2, Fig. 1, looking in the direction indicated by the arrow.

50 My improved traffic signal for a motor-vehicle comprises a tubular pivotal member 5 adapted to be disposed or arranged longitudinally of said vehicle and supported from

a circular metal bracket 6 arranged at the inner end and facing endwise of said pivotal member. Said bracket (see Fig. 1) is shown secured near its outer circumferential 60 edge, by screws 7, to a member 8 forming a part of or rigid with the rear portion of the body or framework of the vehicle. Said bracket is provided centrally with a screw-threaded hole 10, and the pivotal member 5 65 is circular in cross section from end to end and arranged centrally of said bracket. The inner end portion of said pivotal member is shown screw-threaded externally, and said member is screwed at the hole 10 into the 70 bracket 6. Said bracket has an outwardly offset annular portion 12 which is substantially concentric relative to the pivotal member 5 and arranged centrally between said pivotal member and the outer circumferential 75 edge of the bracket so as to form an annular recess 13 at the inner side of the bracket. Within the recess 13 are nuts 14 threaded onto the shanks of bolts 15 which are parallel with the pivotal member 5 and 80 extend through a substantially vertical annular metal plate 16 which extends around and faces endwise of but is spaced from said pivotal member and is arranged opposite the outer side of the bracket 6. The bolts 15 85 have their heads countersunk in the plate 16 which is provided centrally with an annular flange 17 which is concentric relative to and snugly embraced by the annular offset portion 12 of the bracket 6, and said portion of 90 said bracket and said flange co-operate in preventing vibration of said plate 16 independently of said bracket and in avoiding strain on the bolts 15. It will be observed that the plate 16 is clamped to the offset portion 12 of the bracket 6 by and between the head of each bolt and the nut 14 on said bolt.

Between the plate 16 and the outer end of the pivotal member 5 is a pulley 18 which is 100 spaced from said end of and rotatably mounted on said pivotal member. The pulley-surrounded central portion of the pivotal member 5 is plain externally and smaller in external diameter than the externally 105 screw-threaded inner end portion of said pivotal member so as to form, at the inner face of said pulley, an annular shoulder 19 on said pivotal member, and said shoulder is arranged to prevent shifting of said pulley 110 into frictional contact with the plate 16. The pulley 18 is rotated in any approved

manner. A suitably driven belt 20 is shown in operative engagement with said pulley. Means for transmitting power to a pulley or 5 rotary member from the steering wheel or other place (not shown) on a motor-vehicle are too well known in the art of operating traffic signals to require further illustration and description in this specification.

A semaphore-arm 21 is rotatably mounted, 10 at the outer face of the pulley 18, on the pivotal member 5 and is therefore arranged between the pulley and the outer end of said pivotal member and spaced from said end. The semaphore-arm, in its normal position, 15 points downwardly and projects below said pulley a suitable distance.

My improved traffic signal also comprises a tail-light comprising a cylindrical casing 22 which surrounds the outer end portion 20 of and extends outwardly beyond the outer end of the pivotal member 5, and said portion of said pivotal member is screw-threaded externally. The casing 22 is shown diametrically larger than the pulley 18 and has 25 its inner head or end 23 rotatably mounted, at the outer side of the semaphore-arm 21, on the rear end of the central and externally plain portion of the pivotal member 5, and said semaphore-arm and said head 23 are 30 secured, preferably removably by screws 24, to said pulley, and consequently said pulley constitutes an actuating member for the semaphore-arm and said casing, and said casing and the semaphore-arm are rotated 35 during the rotation of the pulley. The operation of semaphore-arms on motor-vehicles is too well understood in the art to require description in detail in this specification. Suffice it to state that the semaphore- 40 arm 21 is actuated into a horizontal position to point laterally of the casing 22 in the one direction as indicated by broken lines at 27, Fig. 2, or in the opposite direction as indicated by broken lines at 28, Fig. 2, preparatory to turning of the vehicle in the one direction or the other, and that preparatory to stopping the movement of the vehicle said arm is actuated into an upwardly pointing position in which it projects above said casing as indicated by broken lines at 29, 50 Fig. 2.

The outer end portion of the pivotal member 5 obviously extends into the inner end portion of the interior chamber 30 of the 55 casing 22, and within and centrally of said chamber is an incandescent electric lamp 31 supported from said pivotal member in any approved manner, and said pivotal member houses electric wiring 32 connected to said lamp.

Within the outer end of the casing 22 is the usual red lens 33 of the tail-light, and said lens is removably held in place in any approved manner. The surrounding wall of 65 the chamber 30 is partially formed by four

colorless light-transmitting lenses 34 which are held in place in any approved manner and spaced equidistantly circumferentially of said casing, and in the illustrated normal position of said casing one of the lenses 34 is 70 arranged at the bottom of the casing, another of said lenses 34 is arranged at the top of the casing, and the remaining lenses 34 are arranged at opposite sides respectively of the casing. 75

Two nuts 35 are shown arranged within the inner end portion of the chamber 30 and screwed onto the externally screw-threaded outer end portion of the pivotal member 5 and arranged to prevent displacement of the 80 casing 22 outwardly from said pivotal member. Preferably said pivotal member has its nut-bearing outer end portion smaller in external diameter than its central and externally plain portion, so that an annular shoulder 36 is formed on said pivotal member at the inner end of said nut-bearing portion, and said shoulder prevents movement of the inner nut into frictional engagement with the head 23. 85

The hereinbefore mentioned plate 16 is provided with two laterally spaced lower arms 37 having their inner portions diverging downwardly, and each of said arms extend downwardly to and under the travel or path of the semaphore-arm 21 and has its outer end portion 38 projecting upwardly at the outer side of said path, and a license number plate 39, shown bearing the number "1741" at its outer side or face, is arranged 100 opposite the outer sides of said outer end portions of and supported from said arms. Said license number plate is therefore spaced downwardly from the pivotal member 5 and supported from the bracket 6 and arranged 105 at the outer side of the path of the semaphore-arm and under the inner end portion of the casing 22 and has such arrangement relative to the bottom lens 34 that during the operation of the lamp 31 light is transmitted through said lens and illuminates the number on the license number plate. It will be observed that said lamp and the lenses 34, 110 relatively arranged as shown, constitute means for illuminating the license number 115 plate and the semaphore-arm in any one of the hereinbefore mentioned indicative positions of said arm.

The plate 16 is also provided with two upwardly diverging laterally spaced upper arms 40 extending preferably above and over the pulley 18 and above the casing 22, and a sign consisting of a plate 41 bearing the word "Stop" at its outer side is arranged opposite the outer sides of the upper 120 portions of and supported from said arms. It will be observed therefore that the plate 41 is spaced upwardly from the pivotal member 5 and supported from the bracket 6. The plate 41 has such arrangement relative 125 130

to the casing 22 that light transmitted from within the chamber 30 through the lens 34 at the top of said casing illuminates said sign.

5 What I claim is—

1. In a traffic signal for a motor-vehicle, a pivotal member adapted to be arranged longitudinally of the vehicle, a bracket supporting said pivotal member and adapted to be carried by the vehicle, a semaphore-arm supported from and movable circumferentially of said pivotal member and pointing downwardly in its normal position and adapted to be actuated into the one or the other of two oppositely and laterally pointing indicative positions or into an upwardly pointing indicative position, means for actuating the semaphore-arm, means for illuminating the semaphore-arm in any one 20 of the aforesaid indicative positions of the semaphore-arm, and a stop-indicating sign spaced upwardly from the aforesaid pivotal member and arranged at the inner side of the path of the semaphore-arm and supported from the aforesaid bracket.

2. In a traffic signal for a motor-vehicle, a pivotal member adapted to be disposed longitudinally of the vehicle, a bracket supporting said pivotal member and adapted to be carried by the vehicle, a plate arranged at the outer side of and secured to said bracket and facing endwise of said pivotal member, a semaphore-arm supported from and movable circumferentially of said pivotal member and arranged between said plate and the outer end of said pivotal member and spaced from said plate and pointing downwardly in its normal position and adapted to be actuated into the one or the other of two oppositely and laterally pointing 30 positions or into an upwardly pointing position, means for actuating the semaphore-arm, and a stop-indicating sign spaced upwardly from said pivotal member and arranged at the inner side of the path of the semaphore-arm and supported from the aforesaid plate.

3. In a traffic signal for a motor-vehicle, a pivotal member adapted to be disposed longitudinally of the vehicle, a bracket supporting said pivotal member and adapted to be carried by the vehicle, a substantially vertical plate arranged at the outer side of

and secured to said bracket and facing endwise of said pivotal member and having upwardly projecting laterally spaced arms, a 55 semaphore-arm supported from and movable circumferentially of said pivotal member and arranged between said plate and the outer end of said pivotal member and spaced from said plate and pointing downwardly in its normal position and adapted to be actuated into the one or the other of two oppositely and laterally pointing positions or into an upwardly pointing position, 60 means for actuating the semaphore-arm, and a stop-indicating sign spaced upwardly from the aforesaid pivotal member and arranged at the inner side of the path of the semaphore-arm and supported from the 65 aforesaid arms of the aforesaid plate.

4. In a traffic signal for a motor-vehicle, a pivotal member adapted to be disposed longitudinally of the vehicle, a bracket supporting and extending circumferentially of 75 said pivotal member and adapted to be carried by the vehicle and having an outwardly offset annular portion which is substantially concentric relative to and spaced from said pivotal member, a plate surrounding and 80 facing endwise of said pivotal member and arranged at the outer side of and secured to said portion of said bracket and having an annular flange embraced by said portion of said bracket, a semaphore-arm supported 85 from and movable circumferentially of said pivotal member and arranged between said plate and the outer end of said pivotal member and pointing downwardly in its normal position and adapted to be actuated into the 90 one or the other of two oppositely and laterally pointing positions or into an upwardly pointing position, means for actuating the semaphore-arm, and a stop-indicating sign spaced upwardly from the aforesaid pivotal 95 member and arranged at the inner side of the path of the semaphore-arm and supported from the aforesaid plate.

In testimony whereof, I sign the foregoing specification, in the presence of two witnesses.

BENNO B. LEUSTIG.
